STARTER MECHANISM FOR MOTORS

Leo T. Kincannon, Milwaukee, Wis., assignor to
 Metal Products Corporation, a corporation of
 Wisconsin

Original application April 14, 1943, Serial No.
 482,967. Divided and this application August
 25, 1944, Serial No. 551,198

6 Claims. (Cl. 123—185)

1

The invention relates to starters for small motors.

This application is a division of my copending application Serial No. 482,967, filed April 14, 1943, and relates more particularly to the starter mechanism shown, described, and claimed in said application, and the general object of this invention is to provide a starter mechanism which will be less likely to fail and which can be readily and economically manufactured.

One object of the invention is to provide a starter mechanism which eliminates the use of the usual separate ratchet dogs and their springs and provides a simple automatically releasable clutch plate to connect the starter impulse mechanism to the engine shaft.

The invention further consists in the several features hereinafter set forth and more particularly defined by claims at the conclusion hereof.

In the drawings:

Fig. 1 is an enlarged elevational view, partly in cross-section, showing the starter mechanism;

Fig. 2 is a detailed horizontal cross-sectional view taken on the line 2—2 of Fig. 1;

Fig. 3 is a vertical cross-sectional view taken on the line 3—3 of Fig. 1.

In the drawings, the numeral 23 designates generally the starter mechanism, 20 the motor shaft, and 108 the fly-wheel fixed on the shaft 20 and rotatable therewith.

The starter mechanism includes an impulse or torque producing mechanism and an automatic clutch mechanism for connecting said torque producing mechanism to the engine shaft 20 to turn the same to start the motor.

The clutch mechanism includes a fixed jaw clutch member or the plate 150 which is fixed to the flywheel 108 by screws 151. The plate 150 has a plurality of circumferential apertures 152 which are engaged by depending lugs or jaws 153 on an actuator or fixed jaw clutch plate 154. The plate 154 is mounted on a hub or shaft 156 in the top of the fixed casing 157.

The hub 156 which is concentric with the shaft 20 has a larger diameter 158 which has a working fit in the upper part of a bearing 160 and a smaller diameter 161 which has a working fit in the lower part of the bearing 160. A spring 163 urges the hub 156 and plate 154 into its uppermost position in which the lugs 153 are out of engagement with the holes or apertures 152 in the plate 150.

The actuator plate 154 is operated or moved to engaging position by a plurality of cam fingers 170 which depend from a pulley 171. In order

to permit the cams 170 to act on the plate, a spring 165 (Fig. 2) embraces the upper end of the diameter 161 and has a free end receivable in a slot 166 in the bearing. The spring 165 acts as a drag in one direction which permits the plate 154 to move down under the influence of the cam surface 170 while allowing the plate 154 to rotate freely in the opposite direction. The spring 165 as shown in Figs. 1 and 2 cooperates with the part 161 of the shaft 156 to form a one-way or overrunning brake. The pulley 171 has a hub 173' which is mounted to rotate about the bearing 160 in the top of the casing 157 and is urged into retracted position by a spring 173. The pulley is turned or operated by a rope or cord 175, one end of which projects through an opening 157' and is maintained outside the casing.

To start the motor the carburetor (not shown) is flooded in the usual manner and the cord 175 pulled to rotate the pulley. Rotation of the pulley 171 brings the cam surfaces on the fingers 170 into engagement with the top of the actuator plate 154 forcing said plate downwardly into engagement with the plate 150, it being noted from Fig. 3 that the fingers 170 project through openings 154' in said plate 154 and act as wedges. Downward movement of the actuator plate 154 brings its lugs 153 into engagement with one side of the holes 152 and further rotation of the pulley 171 rotates the shaft 20, causing the engine or motor, not shown in detail herein, to become filled with explosive mixture which is compressed and fired as usual to start the engine rotating under its own power.

When the motor starts, the rotation of the plate 150 relative to the plate 154 is reversed and the trailing edges of the apertures 152 in the plate 150 contact cam surfaces 153' on the trailing edges of the lugs 153 to force the plate 154 free of the plate 150 and other rotating parts of the engine. The spring 163 also acts to normally urge the plate 154 to a disengaging position, so that in case the cord 175 has been pulled out to its full extent before the motor starts or the motor fails to start, the plate 154 will be disengaged from the plate 150 and the spring 173 will be free to turn the pulley 171 back to a starting position.

It will be noted that the cord operated pulley 171 with its fingers 170 provides a torque producing mechanism which acts to move the clutch plate 154 into engagement with the clutch plate 150 on the motor and which is returned to its initial starting position by the spring 173. The drag produced by the spring 165 acts only in one

direction, that is, while the pulley 171 is being turned to turn the motor, but releases when the motor starts to allow the plate 154 to be turned freely in the opposite direction as the plate 154 is moved upwardly by the spring 163 out of engagement with plate 150.

It will be noted that the flywheel 108 itself is provided with apertures in line with the apertures in the plate 150 and that the plate simply forms a wear surface for the tops of the apertures in said flywheel.

I desire it to be understood that this invention is not to be limited to any particular form or arrangement of parts except in so far as such limitations are included in the claims.

What I claim as my invention is:

1. In a starter for a motor having a flywheel with apertures therein, a pulley, a spring attached to said pulley and adapted to rotate the pulley in one direction, a cord engaged with said pulley and adapted to rotate the pulley against the action of said spring, an actuating plate mounted concentrically with said pulley and having a limited movement in a plane perpendicular to the pulley, a cam member mounted on said pulley and in constant engagement with said plate, said cam being adapted simultaneously to rotate said plate and having fixed cam portions engageable with said plate to move the same toward said flywheel, and fixed lugs on said plate engageable in the apertures in the flywheel to rotate the latter.

2. In a starter for a motor having a flywheel with an aperture in the upper end thereof, said starter comprising a pulley, a cord wound about said pulley and adapted to rotate the same, an actuator plate movable axially toward the flywheel, a fixed lug on said actuator plate engageable with the aperture in the flywheel to rotate the same, and cam means on the pulley simultaneously to rotate the actuator plate and cause the same to move toward the flywheel and actuate the motor.

3. In a starter mechanism of the character described, the combination with a manually revolute member and an engine shaft, of a clutch for connecting said member with said shaft including a fixed jaw clutch member having lugs forming relatively fixed jaws and movable with said revolute member and lengthwise relative thereto and a fixed jaw clutch member on said shaft provided with lug engaging recesses and having a driving connection with said lengthwise movable clutch member but releasable therefrom on reverse rotation of said shaft and cam means on said manually revolute member to simultaneously rotate said first named clutch member and cause the same to move toward the second named clutch member.

4. In a starter mechanism of the character described, the combination with a manually revolute member and an engine shaft, of a clutch

for connecting said member with said shaft including a fixed jaw clutch member having lugs forming relatively fixed jaws and movable with said revolute member, means for imposing a drag on the rotation of said clutch member in one direction to produce relative movement between said members, cam means on said revolute member acting on said clutch member to move it lengthwise relative thereto, and a fixed jaw clutch member on said shaft provided with lug engaging recesses and having a driving connection with said lengthwise movable clutch member but releasable therefrom on reverse rotation of said shaft.

15. 5. In a starter mechanism of the character described, the combination with a manually revolute member and an engine shaft, of a clutch for connecting said member with said shaft including a fixed jaw clutch member having lugs forming relatively fixed jaws and movable with said revolute member, means for imposing a drag on the rotation of said clutch member in one direction to produce relative movement between said members, cam means on said revolute member acting on said clutch member to move it lengthwise relative thereto, a fixed jaw clutch member on said shaft provided with lug engaging recesses, said clutch members having a direct drive connection with each other in one direction, and a wedge connection in the opposite direction to automatically release said lengthwise movable clutch member.

6. In a starter mechanism of the character described, the combination with a manually revolute member and an engine shaft, of a clutch for connecting said member with said shaft including a fixed jaw clutch member having lugs forming relatively fixed jaws movable with said revolute member, a one way overrunning spring brake for imposing a drag on the rotation of said clutch member in one direction to produce relative movement between said members, cam means on said revolute member acting on said clutch member to move it lengthwise relative thereto, and a fixed jaw clutch member on said shaft provided with lug receiving recesses and having a driving connection with said lengthwise movable clutch member but releasable therefrom on reverse rotation of said shaft.
